US00D794003S

(12) **United States Design Patent** (10) **Patent No.:** **US D794,003 S**
Chen et al. (45) **Date of Patent:** **** Aug. 8, 2017**

(54) **PORTABLE ELECTRONIC DEVICE**

(71) Applicant: **HTC Corporation**, Taoyuan, Taoyuan County (TW)

(72) Inventors: **Hung-Yu Chen**, Taoyuan (TW); **Meng-Sheng Chiang**, Taoyuan (TW); **Chih-Ling Chien**, Taoyuan (TW)

(73) Assignee: **HTC CORPORATION**, Taoyuan (TW)

(**) Term: **15 Years**

(21) Appl. No.: **29/533,258**

(22) Filed: **Jul. 15, 2015**

Related U.S. Application Data

(60) Division of application No. 29/460,891, filed on Jul. 16, 2013, now Pat. No. Des. 739,391, which is a continuation-in-part of application No. 29/454,474, filed on May 10, 2013, now Pat. No. Des. 732,498, which is a continuation-in-part of application No. 29/443,348, filed on Jan. 16, 2013.

(57) **CLAIM**

The ornamental design for portable electronic device, as shown and described.

DESCRIPTION

FIG. 1 is a front perspective view of a portable electronic device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines, which show portions of a portable electronic device, form no part of the claimed design.

1 Claim, 7 Drawing Sheets
